UNITED STATES PATENT OFFICE.

ADOLPH BLOOM, OF LANSING, MICHIGAN.

WIRE STRETCHER.

1,412,447.

Specification of Letters Patent. Patented Apr. 11, 1922.

Application filed October 25, 1919. Serial No. 333,295.

To all whom it may concern:

Be it known that I, ADOLPH BLOOM, a citizen of the United States, residing at Lansing, in the county of Ingham and State 5 of Michigan, have invented certain new and useful Improvements in Wire Stretchers, of which the following is a specification.

This invention relates to wire stretchers and has for its primary object the provision 10 of an improved form of stretcher device which can be readily and easily attached to a fence post and moved relative to the post for stretching wire.

A further object is to provide a stretcher 15 which can be conveniently handled by a single person, and which is particularly adapted for active use in stretching any kind of wire; improved locking means being provided whereby the stretching element of the 20 device is held rigid after being adjusted to draw and stretch the wire.

A further object is to provide a device, which aside from its use as a wire stretcher can also be employed for the purpose of 25 lifting fence posts from their positions to permit of their being replaced.

With these and other objects in view, the invention consists of the novel details of construction and combination of parts more 30 fully hereinafter disclosed and particularly pointed out in the claims.

In the accompanying drawings forming a part of this application—

Figure 1 is a plan view of the invention 35 illustrating a wire stretcher.

Figure 2 is a side elevation showing its use as a fence post lifter.

Figure 3 is a view of the locking lever detached from the stretcher arm, and

40 Figure 4 is a view of the post gripping member.

Fig. 5 is a sketch in section showing the bifurcation of the stretcher arm.

As shown in the drawings, the invention 45 comprises a stretcher arm provided with an elongated handle portion 1 of a tapering configuration and a widened portion 2, adjacent the narrow end of the handle; which portion is bifurcated whereby spaced parallel 50 arms 3 are formed. Each arm 3 is provided with a smooth outer edge 4, extending throughout the length of the arm and curving upwardly along the pointed nose 5 at the end of the arm. Each arm engages and 55 supports one end of a pin 6 which is rigid therebetween and to which is connected a

cable or other suitable element 7. The other end of the cable 7 is secured to the handles 8 of the wire gripping pliers 9 in the manner shown in Figure 1. The fence wire, indicated at 10, is secured and gripped between the jaws 11 of the pliers before any pull is exerted on the cable 7, after which the arm 1 is drawn back, tensioning the cable 7 and causing the handles 8 to be 60 drawn toward each other and forcing the jaws 11 tightly against the fence wire.

A post gripping member 12 is disposed between the arms 3 and is pivotally supported therebetween upon a pin 13, which 65 passes through an opening 14, of the ear piece 15 formed on the inner face of the post gripping member and spaced from the lateral edges of this member, as seen to advantage in Figure 4 of the drawing. An 70 enlarged, angularly disposed head 16 is provided on the member 12 and has its inner face curved as at 17 to substantially conform to the curvature of the pointed nose 5 of each of the arms 3. The curvature of 75 these elements permits the device to snugly embrace a cylindrical fence post, as illustrated in Figure 1. The enlarged head is faced off abruptly to provide a flat, face 18, 80 from which project the tooth elements hereinafter referred to.

The locking lever comprises a substantially rectangular portion 20 having handle means 21 integral therewith and reduced at one end to provide shoulders 22 and the projecting portion 23, the latter adapted to be inserted between the arms 3 of the stretcher arm and supported upon a bearing 24. The portion 20 of the lock lever has a suitable opening 25 therethrough into which one end 90 of the member 12 is adapted to be received when the parts of the invention are assembled. One wall 26 of the opening is rounded off as are likewise the shoulders 22 to provide a cam surface permitting the end 27 of the member 12 to ride smoothly thereover, whereby the latter is moved to shift the head 16 forwardly of point 5 when the member 20 is moved in a given direction about its pivot.

Teeth elements 28 are provided on the flat face 18 of the enlarged head 16 and are made rigid therewith. These elements project a suitable distance beyond the face 18 of the head and are to penetrate the post 19 when 95 the member 12 is drawn into engagement 100 with the post.

For stretching wire the device is put to use in the following manner: The head 16 of the gripping member 12 is placed up against post 19 with the points of the teeth in contact therewith, and the rear end of the member lying close up to part 2, resting upon edges 4; the locking lever being disposed in opposite position alongside the stretcher arm. The device is held in position by the operator who grips handle 1 in one hand, and handle 21 in the other hand. To stretch the wire, lever arm 1 is drawn to pull the wire, tooth element 28 serving as the fulcrum about which the arm is turned. When the arm has been so far turned as to have tensioned or stretched the wire to the desired degree, handle 21 is swung upwardly from alongside the arm, causing end 27 of post-gripping member 12 to enter opening 25 after being engaged by cam edge 26, which moves the member about the pivot 13, causing the teeth to bite into the post and to become firmly embedded therein with the flat face of the head engaging the post. This face constitutes a shoulder for the teeth which enables the latter to hold the stretcher device to the post and to successfully withstand the adverse pull of the stretched or tensioned wire. Consequently, having thus locked the stretcher to the post in a firm and secure manner, the operator is free to let go of same and to give his attention to stapling the stretched wire to the fence post. It is therefore, apparent, that with a device of this character, the stretching and stapling of the wire can be successfully and most conveniently accomplished by a single person, whereas, formerly, the services of several have been required.

When used for lifting purposes the device is merely inverted so that the tooth element 28 may bite into the post near the ground line thereof and the handle 21 extends vertically in substantially parallel relation with the post. The member 12 is locked by the lever 20 in the usual manner but in this instance the hump 29 of the enlarged head is used as a fulcrum upon which the device is moved, the handle 1 being drawn back away from the post and downwardly, causing the enlarged head to move in a substantially vertical direction and forcing the post up out of the post hole.

The above constitutes the preferred embodiment of the device but it is to be understood that minor details of construction with respect to the arrangement of the parts may obviously be changed without departing from the spirit of the invention, as herein-after stated.

Having thus fully described my invention, what I claim as new and useful and desire to secure by Letters Patent is:

1. A device of the character described including a stretcher arm having a bifurcated portion, a post engaging member pivoted between the bifurcations and lever means pivoted for movement against this post engaging member, whereby the latter may be moved to hold the arm fixed to a post.

2. A stretcher including in combination with a wire stretching element, of a stretcher arm having a movable tooth portion at one end and a handle at the other end, and a lever means carried adjacent the movable end for moving said toothed portion into engagement with a post, whereby said stretcher arm may be supported therefrom.

3. A device of the character described, including a stretcher arm, a post-gripping member, and lever means for adjusting said member against a post to hold the arm fixed thereto.

4. A device of the character described, including a stretcher arm, post gripping means, pivotally connected to said arm to provide a fulcrum therefor, and means carried by the arm and engageable with said post gripping means for actuating the latter to hold the arm fixed to a given post.

5. A device of the character described, including a stretcher arm having a handle at one end and a bifurcated portion at the other end, an element pivotally supported between the bifurcations and having post-gripping means at one end, and lever means on the stretcher arm for movement against the other end of the pivoted element, to cause the gripping means thereof to bite into the post and to hold the stretcher arm fixed thereto.

In testimony whereof I affix my signature in presence of two witnesses.

ADOLPH BLOOM.
